Des. 236,313
Patented Aug. 19, 1975

236,313

CORN GRATER

Emeline H. Malpas, The Secret Farmhouse,
Little River, Calif. 95456

Filed Jan. 11, 1974, Ser. No. 432,737

Term of patent 14 years

Int. Cl. D7—04

U.S. Cl. D7—47

FIG_1

FIG_2

FIG_4

FIG_3

FIG_5

FIG_6

FIG. 1 is a perspective view of a corn grater showing my new design;

FIG. 2 is a top plan view of the corn grater;

FIG. 3 is a front elevation view of the corn grater;

FIG. 4 is a right side elevation view of the corn grater;

FIG. 5 is a left side elevation view of the corn grater;

FIG. 6 is a bottom view of the corn grater.

I claim:

The ornamental design for a corn grater, as shown and described.
